CLAIM

The ornamental design for a rotating anti-theft tag, as shown and described.

DESCRIPTION

FIG. 1 is a perspective view of a rotating anti-theft tag for an electronic article surveillance device showing our new design;

FIG. 2 is a front elevational view of FIG. 1, the rear elevational view being identical to the front elevational view;

FIG. 3 is a top plan view of FIG. 1;

FIG. 4 is a bottom plan view of FIG. 1; and,

FIG. 5 is a right side elevational view of FIG. 1, the left side elevational view being identical to the right side elevational view.

The portions shown in broken lines are included for illustrative purposes only and form no part of the claimed design.
